UNITED STATES PATENT OFFICE.

GEORGE FORTON, OF DETROIT, MICHIGAN.

COMBINED PIPE AND NUT WRENCH.

Application filed September 21, 1922. Serial No. 589,523.

To all whom it may concern:

Be it known that I, GEORGE FORTON, a citizen of the United States of America, residing at Detroit, in the county of Wayne 5 and State of Michigan, have invented certain new and useful Improvements in a Combined Pipe and Nut Wrench, of which the following is a specification, reference being had therein to the accompanying 10 drawings.

One of the objects of my invention is to provide a combined pipe and nut wrench, wherein simple and effective means is employed, in a manner as hereinafter set 15 forth, for rendering the pipe gripping action of the wrench temporarily inactive so that the wrench may be used for gripping and rotating a nut or other object having facets or flat surfaces that may be 20 engaged by the wrench.

Another object of this invention is to provide a wrench of the above type having a pivoted spring-pressed shank and gripping jaw which may be tilted to permit of the jaw being easily placed in engagement with the pipe or other object having a curvilinear surface, and provision is made for adjusting the shank with a stop to prevent an extreme adjustment which 25 would release the shank relative to the wrench.

A further object of this invention is to provide a wrench of the above type where- 30 in all the parts are compactly assembled and well protected to permit of the wrench being roughly handled without any danger of parts thereof being broken. The wrench is also comparatively light in weight, without sacrificing strength, and the construc- 35 tion entering into the wrench will be hereinafter specifically described and then claimed.

Referring to the drawing,

Figure 1 is a side elevation of a portion 40 of the wrench, partly broken away and partly in longitudinal section;

Fig. 2 is a longitudinal sectional view of the wrench taken on the line II-II of Fig. 1;

Fig. 3 is a cross sectional view of the wrench taken on the line III-III of Fig. 1, and

Fig. 4 is a similar view taken on the line IV-IV of Fig. 1.

In the drawing the reference numeral 1

denotes a handle bar having its outer end provided with a head 2 and mounted on said head and extending therein is a serrated jaw 3 which may be held by a rivet 4 or other fastening means.

5 denotes a strap, oblong in cross section, said strap having apertured ears 6 pivotally connected to the sides of the head 2 by rivets 7 or other pivotal means extending transversely of said head which 60 is cut away, as at 8, to provide clearance for the ears 6.

9 denotes a shank rectangular in cross-section and slidable in the strap 5, said shank having a fixed or integral serrated 70 jaw 10 confronting the jaw 3 and adapted to cooperate therewith in gripping a pipe, nut or the like. Opposed walls of the shank 9 are threaded, as at 11, and engaging said threads is a cylindrical interiorly 75 screwthreaded nut 12 set in a transverse slot 13 provided therefor in the strap 5, adjacent the inner end of said strap.

14 denotes a transverse partition carried by the inner end of the strap 5 and this 80 partition engages the inner end of the nut 12, while the outer end of said nut abuts the strap 5 and a spring pressed abutment 15 set in said strap, between the handle bar 1 and the shank 9. The abutment 15 is 85 engaged by a bowed auxiliary spring 16 and the partition 14 is engaged by a bowed main spring 17, said spring having ends thereof mounted in a transverse slot or kerf 18 provided therefor in the head 2 90 adjacent the rivet 7. The expansive force of the springs 16 and 17 holds the inner end of the strap 5 normally away from the handle bar 1, so that the jaw 10 will be in proximity to the jaw 3, but may be 95 sprung outwardly from said jaw when placing the wrench in engagement with a pipe or other object.

19 denotes a channel shape latch slidable on the inner edge of the handle bar 1, said 100 latch being retained in engagement with the handle bar by a flat spring or resilient member 20 mounted on the inner edge of the handle bar 1. The latch 19 is adapted to be shifted into recesses 21 provided 105 therefor in the inner end of the strap 5 and when said latch engages the strap it is held stationary so that the shank 9 will not tilt when being used to engage a nut. Making the strap 5 non-tiltable does not 110

interfere with adjustment of the shank 9 by the nut 12 in the strap 5.

22 denotes a stop pin extending transversely of the shank 9, adjacent its inner end and when the shank 9 is distended by adjusting the nut 12, the stop pin 22 is adapted to enter the nut 12 and engage the inner end of the strap 5; the location of the stop pin 12 being such that the inner end of the shank 9 remains in threaded engagement with the nut 12 to be adjusted thereby.

By making the abutment 15 detachable relative to the handle bar 1, easy access may be had to the springs 16 and 17 and 15 by said abutment being interposed between the head 2 and the nut 12 the nut 12 cannot bind against the strap 5 and can 10 be freely rotated in the slot 13 of said 20 strap.

One embodiment of my invention has been illustrated, but it is to be understood that the structural elements are susceptible

to such changes as fall within the scope of the appended claim.

25

What I claim is:

A wrench comprising a handle bar having a jaw, a strap embracing said handle bar and pivotally connected thereto, a shank 30 slideable in said strap and provided with a jaw confronting the jaw of said handle bar, means between said handle bar and said shank maintaining said shank normally tilted relative to said handle bar, a nut in said strap in threaded engagement 35 with said shank and adapted for shifting said shank relative to the strap, and a latch slideable on said handle bar into said strap and adapted to prevent tilting of said strap relative to said handle bar.

In testimony whereof I affix my signature in presence of two witnesses.

GEORGE FORTON.

Witnesses:

H. C. UNDERWOOD,
ARTHUR MINNICK.
